PNEUMATIC THREAD REMOVER FOR LOOMS

George N. Peterson, Grafton, Mass., assignor to
Crompton & Knowles Loom Works, Worcester,
Mass., a corporation of Massachusetts

Application July 30, 1948, Serial No. 41,673

19 Claims. (Cl. 139—256)

1

This invention relates to weft replenishing looms and more particularly to an improved pneumatic thread remover for the thread of an outgoing bobbin which remains after a weft replenishing operation.

In weft replenishing looms the thread of the discharged depleted shuttle remains attached to the cloth selvage after a replenishing operation. Pneumatic devices have been proposed heretofore to attract this thread and remove it from the loom after it has been cut at the selvage, but such devices, whether operating with continuous or intermittent subatmospheric pressures, have been inefficient in their use of air power.

It is an important object of the present invention to provide a pneumatic thread removing system having a controller to vary the cross section of the air and thread passage, wherein the leakage of air into the system is reduced to a minimum sufficient to prevent escape of a thread on non-transferring beats of the loom, and wherein the minimum cross section of the air passage is considerably increased on replenishing beats to provide additional pneumatic attraction to draw a thread into the remover.

Bobbin changing looms generally have a transferrer arm pivoted on a stud on which it turns to press a fresh bobbin into the depleted shuttle. It is another object of the invention to provide a thread remover having two degrees of pneumatic attraction for a thread under control of the transferrer arm.

Bobbin changing ordinarily occurs when the lay is at front center, but the replenished shuttle is not picked until some later time in the loom cycle, such as top center, when the lay is moved rearwardly. If the thread of the outgoing bobbin should be pinched between the front wall of the shuttle and the binder it will not be able to respond to the increased pneumatic attraction until after picking. As the shuttle leaves the box the thread will be released and can then respond to pneumatic attraction. It is a still further object of the invention to operate the aforesaid controller so that the pneumatic thread remover will have its period of increased pneumatic attraction continue until after picking to be able to attract a previously held thread.

With these and other objects in view which will appear as the description proceeds, the invention resides in the combination and arrangement of parts hereinafter described and set forth.

In the accompanying drawings, wherein a convenient embodiment of the invention is set forth, Fig. 11 is a side elevation as viewed from the

2

center of the loom of a weft replenishing mechanism having the invention applied thereto, parts of the loom frame and lay being in cross section.

Fig. 2 is a plan view looking in the direction of arrow 2, Fig. 1, the stand for the reserve bobbin magazine being in section,

Fig. 3 is a side elevation on an enlarged scale of the controller shown in Fig. 1, one of the parts thereof being shown in two different positions by solid and dotted lines,

Fig. 4 is a section on line 4—4 of Fig. 3 showing on an enlarged scale the relation of the three air passages which form a significant part of the invention,

Fig. 5 is a detailed section on an enlarged scale on line 5—5, Fig. 3, showing the normal relation of two of the aforesaid thread passages,

Fig. 6 is a plan view looking in the direction of arrow 6, Fig. 3, and

Fig. 7 is a fragmentary side view of one of the members of the controller for the air passages of the remover.

Referring particularly to Figs. 1 and 2, the loom frame 10 has mounted thereon a support 11 carrying a pivot 12 for a reserve bobbin magazine M. The support 11 has fixed thereon a stud 13 serving as a pivot for a transceiver arm 14 provided with a latch 15. The lay L is provided with a shuttle box 16 the front wall 17 of which may be slotted as at 18 to receive a thread cutter 19. A forwardly extending bunter 20 on the lay normally passes above the latch 15, but on weft replenishing beats of the loom the latch 15 is raised by well-known means into the path of the bunter and as the lay advances the transceiver arm 14 turns on stud 13 to move a reserve bobbin from the magazine into the shuttle S in shuttle box 16. At the same time cutter 19 moves rearwardly to cut the filling thread F extending from the shuttle eye E of the shuttle S toward the selvage of the adjacent cloth C. These operations occur as the lay approaches front center and the fresh bobbin will be fully inserted into the shuttle and cutter 19 will have cut the filling F adjacent to the shuttle eye by the time the lay reaches front center position, or the extreme right hand position which it can assume as viewed in Fig. 1.

While a particular form of thread cutter has been shown herein the invention is not necessarily limited to a cutter operating adjacent to the shuttle eye E, and any other approved form of thread cutter may be employed. If the cutter 19 is employed that part of the filling F extending between the front of the shuttle and the

box wall 17 may be pinched between these parts until the shuttle is picked by the picker 21 as the lay reaches top center while moving rearwardly. As the lay approaches its back center position a vertical rod 22 will move upwardly. Rod 22 is reciprocated vertically by a connection to the lay, not shown herein but similar to that shown, for instance, in prior Patents Nos. 2,219,768 and 2,336,321. As the lay moves forwardly rod 22 descends, and as the lay moves rearwardly the rod rises. The rod has a complete reciprocation for every beat of the loom. The transerrer arm has extending laterally therefrom a rod 23 for a purpose to be described.

The loom frame supports a temple 25 having the usual temple cutter 26 which will ordinarily operate when the lay is on front center to cut any thread extending from the cloth C toward the shuttle box and in the path of the cutter 26. The latter is ordinarily set far enough forward in the loom so that it will not cut the thread F on the transferring beat of the loom, but will cut this thread several picks later due to advance movement of the cloth.

The loom may have a thread collector 27 in the form of a hollow cylinder connected at its upper end to a pipe or hose 28 by means of which subatmospheric pressures are created within the cylinder 27, either continuously or intermittently. The cylinder rests on a base 29 supporting a tube 30 which is connected to the interior of cylinder 27.

The matter thus far described may be of usual construction and operate in usual manner.

The present invention provides a controller K for efficiently using the reduced air pressure in the cylinder 27 to prevent retrograde escape of a thread in the remover, and also provide increased pneumatic attraction for that part of the thread F which remains connected to the cloth after a replenishing operation. The controller comprises two members which are mounted for movement relative to each other on stud 13. One of these members, designated at 35 is held in adjusted angular position on stud 13 by a set screw 36. This member 35 has fitted thereto a pipe or tube 37 having a relatively large primary air and thread passage 38 therein communicating with a similar passage 39 in member 35. The tube 37 is connected by a hose H to the previously described tube 30, and whenever subatmospheric pressures exist within the cylinder 27 they will also exist in the thread passages 38 and 39.

The other member 40 of the controller comprises a flat plate 41 having a bore 42 to receive the stud 13 so that the plate can pivot on the stud. The plate 41 has an extension or operating arm or element 43 the rear end of which lies under the rod 23 on the transerrer arm, and has also a wing or second element 44 over the rod 22.

The stud 13 has a reduced threaded end 45 provided with a nut 46 which holds a bowed leaf spring 47 against the plate 41. The spring 47 comprises means for holding the plate 41 frictionally against the adjacent flat face 48 of member 35, and serves to hold plate 41 in the two operating positions which it can assume relative to member 35, as will be described.

A tube 50 having a relatively large primary thread and air passage 51 therein is secured in any approved manner, as by welding or soldering, to the plate 41 and is connected by a flexible hose 52 to a thread remover 53 mounted on the temple 25 adjacent to the cloth C. The remover 53 has

a rearwardly opening intake mouth 54 to receive the thread F.

A third or secondary air and thread passage 55 of much less cross sectional area than the passages 38 or 51 is provided by a narrow shallow groove cut in the face 48 of the member 35 on an arc concentric with the axis of stud 13, see Fig. 7. Passage 55 communicates with the air passages 39 and 38 and is long enough to communicate with air passage 51 when member 40 is in the normal position thereof, see for instance Fig. 4.

Under normal conditions during non-transferring beats of the loom the members 35 and 40 will be in their normal relative position shown in full lines in Fig. 4 so that passages 38 and 51 will be out of register and offset relatively to each other and connected by the relatively small air passage 55. Under these conditions the leakage of air into the system will be very small and will be determined largely by the cross sectional area of secondary passage 55. The latter will be large enough to pass the thread F and sufficient air to maintain reduced air pressures in the mouth 54 slightly below atmospheric pressure but sufficient to prevent a thread in the mouth from falling out of it. Normally the rear extension 43 of member 40 will be in the raised position shown in full lines in Fig. 3.

When a weft replenishing operation occurs transerrer arm 14 moves the rod 23 downwardly to rock the member 40 from the full line to the dotted line position shown in Fig. 3 or until the thread passages 38 and 51 register, or are in alignment, as suggested by the dotted lines in Fig. 4. At this time the lay will be on front center and the full effect of the subatmospheric pressures within tube 37 are communicated directly through passage 51 to the remover mouth 54. As a result there is a considerable increase in the volume of air rushing into the mouth 54 and an increase in the pneumatic attraction exerted on thread F. The transerrer arm 14 is a part of the loom which has a motion incident to a replenishing operation of the loom, but the invention is not necessarily limited to arm 14 as a placing means for member 40.

As the lay moves rearwardly after a transferring operation the transerrer arm rises, but the friction between the two members 35 and 40 caused by spring 47 holds the parts in the dotted line position shown in Fig. 3 until after the shuttle is picked from the shuttle box. As soon as the shuttle is picked the thread F, if it had previously been pinched between the front wall 17 and the shuttle, will be released and drawn into the mouth 54 and along the hose 52. As the lay approaches back center the rod 22, acting as a resetting means, will rise and by its engagement with wing 44 will rock the member 40 back to its normal position, thereby moving the thread passage 51 from the dotted to the full line position of Fig. 4 and interposing the air passage 55 as a restricted air conducting duct between passages 38 and 51. If the thread F should extend from passage 51 to passage 38 prior to return of the members to normal position it will be moved along passage 55 as rod 22 raises wing 44. At a subsequent time the temple cutter 26 will sever the thread F close to the cloth, and the thread 70 will then be drawn through passages 51, 55, 39 and 38 to the thread collector 27.

From the foregoing it will be seen that the invention provides a pneumatic thread remover system providing variable degrees of pneumatic attraction in mouth 54 for the thread F, the

attraction being relatively low under normal conditions and being relatively high at the time of a bobbin transfer. This variation in ability to attract a thread is due to the fact that the system has two degrees of pneumatic resistance to the passage of air therethrough, the resistance being normally relatively high to create a low degree of attraction, and being considerably reduced at the time of a weft replenishing operation to permit an increase in the pneumatic attraction. The reduced pneumatic attraction will always be sufficient to hold a thread in the mouth 54, but will be low enough to reduce leakage of air into the system to a minimum compatible with retention of a thread in the mouth. The relatively large primary air passages 38 and 51 are normally offset with respect to each other and connected by the relatively small secondary passage 55 which is large enough to pass a thread but small enough to conserve the subatmospheric pressures within the system. The spring 47 acts to hold the large or primary air passages in alignment until after the shuttle has been picked on a weft replenishing beat of the loom, thereby permitting the system to attain control of the thread F even though the latter had been pinched between the shuttle and box wall 17 prior to picking. The controller K comprises two relatively movable members each having a relatively large air passage therein and at least one of them having a restricted air duct or passage 55. The invention is not limited to the presence of this restricted duct in member 35, and it will be sufficient if it is in either of the members, or partly in each of them. While the invention has been used in connection with cylinder 27 serving as a source of continuous subatmospheric pressures, it is not thus limited, since the pressures within cylinder 27 may if desired be produced intermittently as has been done heretofore.

Having thus described the invention it will be seen that changes and modifications of the foregoing specific disclosure may be made without departing from the spirit and scope of the invention.

What is claimed as new is:

1. In a pneumatic thread remover system for a weft replenishing loom having a thread remaining subsequent to a replenishing operation, the system having an air and thread passage with a source of subatmospheric pressures at one end of the passage and an intake mouth for the thread at the other end of the passage, a controller in the system intermediate said source and mouth through which the air passage extends, said controller capable of assuming two positions in one of which the minimum cross section of that part of the air passage in the controller is relatively small and in the other position of which the minimum cross section of said part of the passage in the controller is relatively large, and means operating incident to a replenishing operation of the loom changing said controller from said one position thereof to said other position thereof.

2. In a pneumatic thread remover system for a weft replenishing loom having a thread remaining subsequent to a replenishing operation, the system having an air and thread passage therethrough, a controller in said system for varying the cross-sectional area of part of the air and thread passage, said controller in the normal position thereof causing said part of the passage to have a relatively small cross section and in

another position thereof causing said part of the passage to have a larger cross section, and means operating incident to a weft replenishing operation moving said controller from said one position thereof to the other position thereof.

3. In a pneumatic thread remover system for a weft replenishing loom having a thread remaining subsequent to a replenishing operation, a controller in the system having three air and thread passages therein one of which is of smaller cross section than the other two passages, said controller in the normal position thereof requiring air to pass through all three of said passages and in another position thereof enabling air to pass from one to the other of said two passages without passing through said one passage, and means operative incident to a weft replenishing operation of the loom to move said controller from the normal position thereof to the other position thereof.

4. In a pneumatic thread remover system for a weft replenishing loom having a thread remaining subsequent to a replenishing operation, a controller in said system having relatively movable members each of which has a primary air passage therein of relatively large cross section and at least one of said members having a secondary air passage therein of relatively small cross section, said controller in the normal position thereof having said primary passages offset with respect to each other to require air moving from one primary passage to the other primary passage to pass also through said secondary passage, said controller in another position thereof having said primary passages in register so that air can pass from one of them to the other without passing through said secondary passage, and means operating incident to a weft replenishing operation of the loom to move the controller from the normal position thereof to said other position thereof.

5. In a pneumatic thread remover system for a weft replenishing loom having a thread remaining subsequent to a replenishing operation, the system having a source of subatmospheric pressures and an intake mouth for the thread, a controller in said system determining the pneumatic resistance to the passage of air from said mouth to said source, said controller in the normal condition thereof causing the system to have a relatively high pneumatic resistance and in another condition thereof causing said system to have a relatively low pneumatic resistance, and means altering said controller from the normal condition thereof to the other condition thereof incident to a weft replenishing operation of the loom.

6. In a pneumatic thread remover system for a weft replenishing loom having a thread remaining subsequent to a replenishing operation, the system having a source of subatmospheric pressures and an intake mouth for the thread, a controller in said system to determine the amount of pneumatic attraction for the thread existing in said mouth, said controller in the normal condition thereof causing said pneumatic attraction to be relatively low but sufficient to prevent retrograde movement of a thread in the mouth in a direction out of said mouth, said controller in another condition thereof causing the system to have a relatively high degree of pneumatic attraction for said thread, and means causing said controller to alter from said normal condition thereof to the other condition thereof incident to a weft replenishing operation of the loom.

7. In a pneumatic thread remover system for a weft replenishing loom having a thread remaining subsequent to a replenishing operation, the system having a source of subatmospheric pressures and an intake mouth for the thread, a controller in said system for determining the degree of pneumatic attraction for said thread existing in said mouth, said controller in one condition thereof enabling said source to exert a relatively low pneumatic attraction only for said thread at said mouth and in another condition thereof enabling said source to exert a relatively high degree of pneumatic attraction for said thread at said mouth, and means altering said controller from said one condition thereof to the other condition thereof incident to a weft replenishing operation of the loom.

8. In a pneumatic thread remover system for a weft replenishing loom having a thread remaining subsequent to a replenishing operation, the system having a source of subatmospheric pressures and an intake mouth for the thread, a controller in said system for determining the degree of pneumatic attraction for said thread existing in said mouth, said controller having two relatively movable members capable of assuming two relative positions in either of which said source is able to exert pneumatic attraction for the thread in said mouth, the controller in one of the relative positions of said members enabling said source to exert a low degree only of pneumatic attraction for the thread in said mouth and in the other relative position of said members enabling said source to exert a higher degree of pneumatic attraction for the thread in said mouth, and means moving said members from said one relative position to the other relative position incident to a replenishing operation of the loom.

9. In a pneumatic thread remover system for a weft replenishing loom having a thread remaining subsequent to a replenishing operation, the system having a source of subatmospheric pressures and an intake mouth for the thread, a controller in said system for determining the degree of pneumatic attraction which said source can create for said thread in said mouth, said controller having three air passages therethrough capable of assuming two relative positions with respect to each other, said controller effective in one relative position of said passages to cause air to pass through all three of said passages in sequence and in another relative position of said passages enabling air to pass from one to another of said passages without being required to pass through the third passage, the third passage having a cross section considerably less than the cross section of the other two passages, and means incident to a replenishing operation of the loom moving said passages from said one relative position thereof to the other relative position thereof.

10. In a pneumatic thread remover system for a weft replenishing loom having a thread remaining subsequent to a replenishing operation, the system having a source of subatmospheric pressures and an intake mouth for the thread, a controller in said system normally enabling said source to exert a low degree only of pneumatic attraction for the thread in the mouth and effective incident to a weft replenishing operation of the loom to exert said source to exert a higher degree for pneumatic attraction for the thread in the mouth.

11. In a pneumatic thread removing system

for a weft replenishing loom having a lay provided with a shuttle box occupied on a replenishing beat of the loom by a shuttle from which extends a thread to be removed, the loom having a weft replenishing operation when the lay is in front center position and picking the shuttle out of said shuttle box during backward movement of the lay, a controller for the system normally in a condition enabling said system to exert a low degree only of pneumatic attraction for the thread in said mouth, said controller in another condition thereof enabling said system to exert a higher degree of pneumatic attraction for said thread in said mouth, means operating incident to a replenishing operation of the loom to alter said controller from said normal condition thereof to said other condition thereof, and means operating subsequent to picking of the shuttle to return said controller from said other condition thereof to said normal condition thereof.

12. In a pneumatic thread removing system for a weft replenishing loom having a lay provided with a shuttle box occupied on a replenishing beat of the loom by a shuttle from which extends a thread to be removed, said system having an intake mouth for said thread and the loom having a weft replenishing operation when the lay is in front center position and picking the shuttle during backward movement of the lay, a controller in said system determining the degree of pneumatic attraction which said system can exert in said mouth for said thread, said controller in the normal condition thereof causing said system to exert a low degree only of pneumatic attraction for the thread in said mouth and in another condition thereof causing said system to exert a higher degree of pneumatic attraction for the thread in said mouth, means operating incident to a weft replenishing operation of the loom to alter the controller from said one condition thereof to the other condition thereof, and means operating subsequent to picking of the shuttle returning said controller to said one condition thereof.

13. A pneumatic controller for the pneumatic thread remover system of a weft replenishing loom having a thread to be removed, said system having a source of subatmospheric pressures and an intake mouth for the thread, said controller comprising two members capable of assuming two different relative positions, said members having thread passages therein so related when said members are in one relative position that said source is capable of exerting a low degree only of pneumatic attraction in said mouth for the thread, said members when in the other relative position thereof having said passages so related that the source is able to exert a higher degree of pneumatic attraction in the mouth for said thread.

14. A pneumatic controller for the pneumatic thread remover system of a weft replenishing loom having a thread to be removed, said system having a source of subatmospheric pressures and an intake mouth for the thread, said controller having a source of subatmospheric pressures and an intake mouth for the thread, said controller having two relatively movable members formed with three air passages one of which has a cross-sectional area less than that of either of the other two passages, said controller in one relative position of said members causing air entering said mouth and moving toward said source to move through all three of said passages and said controller in another relative position of said mem-

bers permitting air entering said mouth to move toward said source by moving through said two passages only.

15. A pneumatic controller for the pneumatic thread removing system of a weft replenishing loom having a thread to be removed, said system having a source of subatmospheric pressures and an intake mouth for the thread, said controller capable of assuming two conditions in one of which said controller creates a relatively high degree of pneumatic resistance to the passage of air from said mouth to said source, and said controller in another condition thereof creating a comparatively low degree of pneumatic resistance to the passage of air from said mouth to said source.

16. In a pneumatic controller for the pneumatic thread removing system of a weft replenishing loom having a thread intake mouth and a source of subatmospheric pressures, said controller having two relatively large primary air passages therein and having also a relatively small secondary air passage therein, one primary passage connected pneumatically to said mouth and the other connected pneumatically to said source and said secondary passage connected pneumatically to one of said primary passages, said controller in one condition thereof requiring air moving from said mouth to said source to move through all of said passages and in another condition thereof requiring air moving from said mouth to said source to pass through said primary passages only.

17. In a pneumatic thread removing system of a weft replenishing loom having a thread to be removed, a part operating incident to a weft replenishing operation of the loom, resetting means operating subsequent to a replenishing operation of the loom, said system having an intake mouth for the thread and a source of subatmospheric pressures, and a controller having a plurality of air passages therein pneumatically connected to said mouth and source, said controller in one condition thereof having the air passages therein so related as to create a relatively high degree of pneumatic resistance to passage of air through the controller, and said controller in another condition thereof having the air passages therein so related as to create a lower degree of pneumatic resistance to the passage of air through the controller, said part of the loom when operating changing the controller from said one condition thereof to the

other condition thereof, and said resetting means subsequently returning the controller from the other condition thereof to said one condition thereof.

- 5 18. In a pneumatic controller for the pneumatic thread removing system of a weft replenishing loom having a thread to be removed, the loom having a part operating incident to a weft replenishing operation of the loom and having 10 resetting means operating subsequent to a weft replenishing operation, said controller comprising two relatively movable members having air passages therein, one of said members having an element for engagement by said part of the loom to move said one member to a position relative to the other member such that said air passages impose a relatively low degree of pneumatic resistance to passage of air through the controller, and said one member having another element for engagement of said resetting means to move said one member to a position relative to the other member such that said air passages impose a relatively high degree of pneumatic resistance to passage of air through said controller.
- 15 20 25 29 30 35 40 45
19. Two members for the control of a pneumatic thread removing system of a weft replenishing loom having an intake mouth for a thread and a source of subatmospheric pressures, said two members each having a relatively large primary air passage therein and one of said members having a relatively small secondary air passage therein communicating with the primary passage therein, said two members when in one relative position thereof requiring air passing through the primary passages to pass also through the secondary passage, and said member when in another relative position enabling air to pass through said primary passages without passing through said secondary passage.
